LAPPING MACHINE

Raymond A. Cole, Worcester, Mass., assignor to
Norton Company, Worcester, Mass., a corpora-
tion of Massachusetts

Application July 6, 1936, Serial No. 88,955

12 Claims. (Cl. 51—118)

This invention relates to lapping machines, and more particularly to an improved automatically operated lapping machine.

One object of this invention is to provide a simple, thoroughly practical lapping machine in which the relative approaching movement of the lapping elements is automatically controlled. Another object of this invention is to provide a lapping machine in which the lapping elements are moved relatively toward each other for a given lapping operation and after a predetermined interval of lapping are automatically separated. A further object of this invention is to provide a lapping machine in which the lapping elements are caused to move relatively into operative lapping engagement with the work pieces at a relatively high pressure for a predetermined time interval, after which the pressure is automatically reduced to permit a finish lapping operation for a predetermined period.

A further object of this invention is to provide an automatic control device for a lapping machine which moves the lapping elements into lapping engagement with the work pieces and automatically applies a predetermined pressure to rough lap the work pieces for a definite time interval, after which the pressure is reduced to a finish lapping pressure and the lapping operation continues for a further predetermined period, after which the lapping elements are automatically separated and the relative rotation thereof is stopped. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

40 In the accompanying drawings in which is shown one of various possible embodiments of the mechanical features of this invention,

Fig. 1 is a diagrammatic view, showing the drive for the lapping wheels and the cage and the hydraulic system for controlling the relative approaching and receding movement of the laps as well as an electrical wiring diagram for controlling the fluid pressure system; and

Fig. 2 is a side elevation of an improved lapping machine, having parts broken away and shown in section to more clearly show the construction.

A lapping machine has been illustrated in the drawings comprising a base 10 which supports a 55 rotatable spindle 11 which in turn supports a

spider 12 at its upper end. The spider 12 supports a lapping wheel mounting plate 13 which in turn supports a lapping wheel 14. The base 10 is provided with an upwardly extending column 15 which supports a rotatable, vertically movable spindle 16. The lower end of the spindle 16 is provided with a wheel supporting plate 17 which is arranged to support a lapping wheel 18 in opposed relation to the lapping wheel 14. The lapping wheels 14 and 18 are arranged for a relative rotary motion as well as a relative approaching and receding movement to produce the desired lapping operation.

In the preferred construction, the upper lapping element or wheel 18 is arranged for a rotary and relative approaching and receding movement. The spindle 16 is supported in anti-friction bearings 20 and 21 which are in turn supported in a vertically slideable sleeve 22. The upper end 23 of the spindle is slidably keyed to a driving pulley 24 which is connected by driving belts 25 to a pulley 26 supported on the upper end of a rotatable shaft 27. An electric motor 30 is provided with a driving pulley 31 and is connected by a belt 32 with a pulley 33 which is rotatably supported on a shaft 34. The shaft 34 carries a worm 40 which meshes with a worm gear 41 mounted on the lower end of a rotatable shaft 42. The shaft 42 is connected by a universal joint 43 with a telescopic shaft 44. The telescopic shaft 44 is in turn connected with a universal joint 45 with the lower end of the rotatable shaft 27. It will be readily apparent from the foregoing construction that when the shaft 34 is rotated, a rotary motion will be transmitted through the worm 40, the worm gear 41, the shaft 42, the universal joint 43, the telescopic shaft 44, the universal joint 45, the shaft 27, the pulley 26, the belt 25, the pulley 24, to rotate the spindle 16 and thereby transmit the desired rotary motion to the upper lapping wheel 18.

Similarly, the shaft 34 carries a worm 50 which meshes with a worm gear 51 mounted on the lower end of the spindle 11 so that when the shaft 34 is rotated, a rotary motion is transmitted through the worm 50, the worm gear 51 and the spindle 11 to rotate the lower lapping element 14 at the desired speed.

In order to facilitate stopping and starting of the machine as desired, a suitable clutch is provided. An internal cone-shaped clutch member 60 is formed within the driving pulley 33 and an external cone clutch member 61 is keyed to the shaft 34. When the clutch member 61 is thrown toward the right (Fig. 2) into engagement with

the clutch member 60, the rotary motion of the pulley 33 will be transmitted to the shaft 34 to drive the upper lap 18 and lower lap 14 at the desired and predetermined speed. In order to facilitate actuation of the clutch, the clutch member 61 is provided with an integral grooved member 62 which is engaged by a movable arm 63. The arm 63 is supported on a slidably mounted rod 64 which is arranged to be moved longitudinally by means of a manually operable control lever 65, which is pivotally supported on a stud 66 on the base 10. The lower end of the lever 65 is connected by a stud 67 with one end of a link 68. The other end of the link 68 is connected by a stud 69 with the end of the slidably mounted rod 64. The rod 64 is slidably mounted in bearings 70 and 71 on the base 10.

In order to hold the clutch member 61 in an operative or inoperative position, an arrow point 72 is mounted on the upper end of the arm 63 and is arranged to be engaged by a spring-pressed roller 73 which serves to hold the clutch either in driving engagement or disengaged, as illustrated in Fig. 2.

It is desirable to provide a braking member so that when the clutch member 61 is disengaged from the clutch member 60, the rotation of the lapping wheels will be immediately stopped. This is preferably accomplished by providing a braking element 74 which is fixedly mounted on the movable clutch member 61 and which is arranged to engage a stationary brake disk 75 which is fixedly mounted on the base 10. When the clutch member 61 is disengaged, the brake disk 74 is moved into engagement with the fixed brake disk 75 to immediately stop the rotation of the shaft 34 and thereby stop the rotation of the lapping elements 14 and 18 respectively.

A plurality of work pieces 80 are mounted in an aperture in a work carrying cage 81 which is carried by driving pins 82 which are rotated and revolved by means of a gear mechanism 83. See, for example, the cage operating mechanism disclosed in the prior United States patent to Indge No. 1,610,527 dated December 14, 1926. This cage operating mechanism is not a part of the present invention and consequently has not been illustrated in detail. For further reference to the cage operating mechanism, reference may be had to the above-mentioned patent.

The upper lapping wheel may be moved vertically to cause the lapping wheel 18 to approach or recede from the wheel 14 by means of a hand wheel (not shown) mounted on the outer end of a rotatable shaft 90. The shaft 90 carries a gear 91 meshing with a rack bar 92 mounted on the rear of the vertically movable sleeve 26. A counterbalance mechanism is provided to counterbalance the weight of the upper lapping wheel 18. This comprises an adjustable weight 93 suspended by a link chain 96 which passes over an idler sprocket 97 which is rotatably mounted on a stud 98 carried by an adjustable bell crank arm 99. A link chain 100 passes over an end portion of the sprocket 97 and also over a sprocket 101 carried by the shaft 90 so that the weight of the movable lap and its associated parts is counterbalanced, thereby facilitating movement of the lap toward and from an operating position.

A power operated mechanism is provided for raising and lowering the upper lap in order that a predetermined and controlled pressure may be applied between the lapping elements and

the work and also in order that the cycle of movement may be readily controlled. A pair of diametrically opposed cylinders 110 and 111 are supported on the frame of the machine on diametrically opposite sides of the vertically movable sleeve 22. The cylinders contain slidably mounted pistons 112 and 113 respectively which are connected by piston rods 114 and 115 respectively with a bracket 116 which is supported at the lower end of the slidably mounted sleeve 22 so that a fluid pressure movement of the upper lapping element causes a vertical approaching or receding movement at the upper lap 18 and applies a substantially uniform pressure at diametrically opposite sides of the lapping element so as to cause a substantially uniform pressure at all points between the lapping elements 14 and 18 and the work pieces 80.

Fluid under pressure is supplied from a reservoir 120 which is preferably located within the base of the machine. A fluid pressure pump 121 which is driven by a driving belt 122 draws fluid from the reservoir through a pipe 123 and forces fluid through a pipe 124 to a reverse or control valve 125. The valve 125 is preferably of a piston type comprising valve pistons 126, 127 and 128. In the position of the parts, as illustrated in the drawings, fluid under pressure passing through the pipe 124 enters a valve chamber 129 between the valve pistons 126 and 127 and passes out through a pipe 130 which conveys fluid under pressure to cylinder chambers 131 and 132 respectively to cause the pistons 112 and 113 to move upwardly into the position as illustrated in Fig. 1, thereby raising the upper lap 18 to an inoperative position. The valve 125 is provided with a valve stem 135 which is connected to a bell crank lever 136 pivotally mounted on a stud 137 on the column 15 of the machine. An arm of the bell crank 136 serves as a control lever 138 whereby the reverse valve may be readily shifted from the front of the machine. During the movement of the pistons 112 and 113 into the positions illustrated in Fig. 1, fluid is exhausted from the cylinder chambers in the upper portions of the cylinders 110 and 111 through a pipe 140, into a valve chamber 141, between the valve pistons 127 and 128, and exhausts through a pipe 142 into the reservoir 120.

In lapping of certain types of work, it is desirable to provide a pressure controlling mechanism which enables the lapping operation to be started with the lapping wheels pressing upon the work at a substantial predetermined pressure to initially or rough lap the work pieces and to then automatically reduce the pressure to produce a final or finish lapping operation. A pressure controlling mechanism is provided so that fluid under pressure applied to the upper ends of the cylinders 110 and 111 will cause the pistons 112 and 113 to exert a downward pressure on the upper lap 18 so that it is forced against the work pieces 80 at a desired predetermined pressure for an initial or rough lapping operation. As illustrated in the drawings, this is accomplished by providing a variable pressure regulating valve 150. This valve is connected by a pipe 151 with the fluid pressure pipe 124. The valve 150 may be adjusted by means of an adjusting screw 152 so that if the pressure supplied by the pump 121 exceeds the desired pressure, a valve member 153 will be raised from its seat against the tension of a spring 154 and will allow the excess fluid under

pressure to exhaust through a pipe 155 into the reservoir.

A second fluid pressure regulating valve 160 is connected by a pipe 161 with the fluid pressure pipe 124. This valve is identical with the pressure regulating valve 150 and comprises a movable valve member 162 which is held against its seat by means of a spring 163 the tension of which may be adjusted by means of an adjusting screw 164. In setting up the machine, the pressure regulating valve 150 is adjusted to give a predetermined pressure for a rough lapping operation on the upper lap, and the pressure regulating valve 160 is adjusted to a predetermined pressure for a final or finish lapping operation.

During the normal use of the mechanism above described, the fluid pressure system is so operated that any pressure in excess of the low pressure to which the valve 160 is set would cause the valve member 162 to rise from its seat and allow the excess fluid under pressure to exhaust through a pipe 165 into the reservoir 120.

In order that either a relatively high or a relatively low pressure may be applied to the upper lapping wheel 18, a valve 170 is inserted within the pipe 161. This valve is arranged so that in the position illustrated in Figs. 1 and 2, fluid under pressure is cut off from the valve 160, thus rendering the low pressure regulating valve 163 inoperative so that the upper lap will be maintained in lapping engagement with the work at a relatively high initial or rough lapping pressure, to which the valve 150 is set. In this position of the parts, the rough lapping operation may proceed to the desired extent. When it is desired to reduce the pressure to a lower or finish lapping pressure, the valve 170 is turned through substantially ninety degrees to allow fluid under pressure to pass through the pipe 161 to the valve 160, thus rendering the low pressure regulating valve 160 operative so that if the fluid under pressure from the pump 121 exceeds the low pressure desired for a finish lapping operation, the valve member 162 opens and allows the excess fluid under pressure to exhaust through the pipe 165 into the reservoir 120.

It will be readily apparent from this disclosure that by manipulation of the valve 170, practically any pressure between the high and low pressure at which the valves 150 and 160 have been set may be obtained.

It is desirable that the fluid pressure system for controlling the movement of the upper lapping wheel 18 be automatically controlled so that when the lever 138 is shifted to start the downward movement of the upper lap, the cycle of operation is automatically continued until the operation has been completed and the lapping element returns to its initial or inoperative position, as shown. It is desirable that the upper lap be moved automatically downward into engagement with the work with a predetermined rough lapping pressure and that the roughing pressure automatically continue for a predetermined time interval, after which the pressure of the upper lap on the work is reduced to a lower predetermined pressure for a final or finish lapping operation for a further predetermined time interval, after which the upper lapping element 18 is moved upwardly to an inoperative position. This cycle of operation is preferably accomplished by means of an electrical control system which is operatively connected to control the fluid pressure system to obtain the desired cycle of operation.

In the preferred construction, an electrical time delay relay 180 is provided. This time delay relay is arranged so that two successive adjustable time intervals may be obtained. The time delay relay 180 is connected to power lines 5 181. In the preferred construction, the time delay relay does not start functioning until the upper lapping wheel is in lapping engagement with the work pieces 80 at a predetermined rough lapping pressure. This is preferably accomplished by providing a normally open limit switch 182 in the circuit between the power lines and the time delay relay. The limit switch 182 is provided with an actuating roller 183 which lies in the path of an adjustable stop 184 carried by 10 the sleeve 22. The stop 184 is adjusted so that when the upper lap 18 moves downwardly into operative contact with the work at a predetermined rough lapping operation, the stop screw 184 engages the roller 183 of the limit switch 182 15 and closes the limit switch which in turn serves to close the circuit so as to start the time delay relay 180 functioning. After a predetermined time interval, the time delay relay 180 makes a contact between the wires 187 and 188 which 20 serves to energize a relay 189 which closes a circuit between the contact members 190 and the relay clapper 191 which serves to close a circuit and to energize a solenoid 192 which is connected by a link 193 with the valve control lever 194 of 25 the control valve 170. The energizing of the solenoid 192 serves to open the valve 170, allowing fluid under pressure to pass through the pipe 161 and to thereby automatically reduce the relatively high initial or rough lapping pressure to 30 a predetermined lower pressure for a final or finish lapping operation.

The finish-up lapping operation at a reduced pressure continues until the time delay relay, after a further predetermined time interval, 40 makes a contact between the wire 187 and a wire 197 which serves to energize a relay 198. This in turn makes a circuit between the contact element 199 and the relay clapper 200 which is connected to energize a solenoid 201 which serves 45 to shift the main control valve 125 into the position as illustrated in Figs. 1 and 2 so that fluid under pressure from the pump 121 is reversed and applied through pipe 130 to the lower cylinder chambers 131 and 132 to raise the upper lap 50 18 into an inoperative position, as illustrated in Fig. 1.

At the same time the relay 198 is energized to close the circuit between the contact element 199 and the clapper 200, a solenoid 204 is energized. The solenoid 204 is connected by a link 205 to move the control lever 65 in a clockwise direction (Fig. 1) to shift the rod 64 toward the left, as viewed in Fig. 1, so as to disengage the clutch member 61 from the clutch member 60, 60 thereby stopping the relative rotation of the lapping wheels 14 and 18 and also stopping the movement of the cage 81.

When the solenoid 201 is energized to reverse the flow of fluid and cause a movement of the upper lap to an inoperative position, it is desirable that this movement be at a rapid rate in order that the idle time of the machine may be reduced to a minimum. It is, therefore, desirable that the electrical control mechanism be so 70 arranged that when the fluid under pressure is reversed, the solenoid 192 will be deenergized so as to allow the released tension of a spring 208 to close the valve 170, that is to move the lever 194 into the position as illustrated in Fig. 1, 75

thereby allowing the relatively high pressure to be applied to the cylinders 110 and 111 to cause a rapid upward movement of the lapping wheel 18. This is preferably accomplished by providing a limit switch 209 which is arranged so that its actuating roller is engaged by an extended portion of the solenoid armature 211. The limit switch 209 is a normally closed limit switch so that when the solenoid 201 is energized to move the parts into the position as shown in Fig. 1, the solenoid armature 211 engages the roller 210 and opens the limit switch 209, thereby deenergizing the solenoid 192 and allowing the released tension of the spring 208 to rapidly close the valve 170 so that the pressure applied to the cylinder chambers 131 and 132 is increased to cause a rapid idle movement of the upper lap to an inoperative position.

In lapping certain types of work, it may be desirable positively to limit the relative approaching movement between the laps 18 and 14. A fixed stop 215 is mounted on a fixed part of the frame of the machine and is arranged in the path of the adjustable stop 184 carried by the sleeve 22. When the upper lap 18 is moved downwardly by the fluid pressure operated mechanism, the adjustable stop 184 engages the fixed stop surface 215 and positively limits the approaching movement of the lapping wheel 18. If the positive stop is used to limit the downward movement of the upper lap, the stop and the limit switch 182 are so arranged that the downward approaching movement of the adjustable stop 184 first engages the roller 183 of the limit switch before or at the time the upper lap 18 engages the work to be lapped and an initial or rough lapping operation at a relatively high pressure is obtained. The downward movement of the upper lap 18 continues under the relatively high pressure until the stop 184 engages the fixed stop 215 at which time the time delay relay serves to render the low pressure regulating valve operative by energizing the solenoid 192, thereby applying a relatively low pressure to the upper lap 18 which continues until the time delay relay after a further predetermined final or finish lapping operation energizes the solenoid 201 to reverse the valve 125 and thereby reverse the flow of fluid to the cylinders 110 and 111 to rapidly separate the lapping wheels 14 and 18.

The operation of this machine is readily apparent from the foregoing disclosure. Assuming the valves and parts to have been previously adjusted to obtain the desired operating pressure, and the electrical parts have been adjusted to actuate at the desired time intervals, a plurality of work pieces 80 are inserted in a plurality of correspondingly shaped apertures in the cage 81. The lever 65 is then moved to engage the clutch member 61 with the clutch member 60 so as to start the relative rotation of the lapping wheels 14 and 18 and also to start the rotary and gyrating movement of the cage 81. The lever 138 is then moved downwardly to rock the bell crank 136 and to shift the valve stem 135 downwardly so that fluid under pressure from the pump 121 passing through the pipe 124 is admitted through the pipe 140 to cause a rapid downward movement of the upper lapping wheel 18. The lapping wheel 18 moves downwardly into contact with the work pieces under a predetermined pressure in accordance with the setting of the pressure regulating valve 150. When the upper lap reaches operating contact with the work pieces 80, the adjustable stop screw 184 engaging the roller 183 of the limit

switch 182 closes the limit switch 182 and starts the electrical time delay relay 180 in operation. The rough or preliminary lapping operation at a relatively high pressure continues for a predetermined time interval, after which the relay 189 is rendered operative to close the contacts 190 and the clapper 191 to energize the solenoid 192 and thereby open the valve 170 and render the low pressure regulating valve 160 operative to reduce the pressure within the system from a relatively high or preliminary lapping pressure to a relatively low or finish lapping pressure. The finish or final lapping operation continues for a further predetermined time interval, after which the relay 198 is energized which in turn closes the contact 199 and clapper 200 which serves to simultaneously energize the solenoids 201 and 204.

The solenoid 201 serves to reverse the control valve and to reverse the flow of fluid within the system to cause an upward or separating movement of the upper lap 18. At the same time the solenoid 204 is energized, the solenoid armature 211 serves to open the limit switch 209 which breaks the circuit to deenergize the solenoid 192, thereby releasing the tension of the spring 208 which closes the valve 170 so that the upper lap 18 moves rapidly to an inoperative position at a high pressure. The energizing of the solenoid 204 serves to disengage the clutch members 60 and 61 and moves the braking elements 74 and 75 into engagement with each other to stop the relative rotation of the lapping elements and the rotating and gyrating movement of the cage 81. The work pieces 80 may then be removed from the machine and replaced with a new set of work pieces to be lapped. This cycle of operation may then be continued on successive batches of work pieces. The entire cycle of operation after the starting of the laps and shifting of the control valve is automatically controlled.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:-

1. A lapping machine of the type having a pair of opposed relatively rotatable lapping elements which are movable relatively toward and from each other and a work carrying cage therebetween, a mechanism to cause a relative approaching and receding movement between said lapping elements, means to control said mechanism to cause either an approaching or receding movement between said lapping elements, a pressure regulating mechanism arranged to maintain said laps in engagement with the work at a predetermined pressure for an initial or rough lapping operation, a second pressure regulating device arranged to maintain said laps in engagement with the work at a second predetermined pressure for a final or finish lapping operation, and means to automatically change from an initial or rough lapping pressure to a final or finish lapping pressure.

2. A lapping machine of the type having a pair of opposed relatively rotatable lapping elements which are movable relatively toward and from each other and a work carrying cage therebe-

5 between arranged to carry a plurality of work pieces through an irregular path between the operative faces of said lapping elements, a mechanism arranged to cause a relative approaching and receding movement between said lapping elements, means including a control lever arranged to cause either an approaching or receding movement between said lapping elements, means to apply a predetermined pressure for an initial lapping 10 operation for a predetermined time interval, a second pressure regulating mechanism arranged to maintain the laps in engagement with the work at a second predetermined pressure for a final or finish lapping operation, and means to automatically control said pressure mechanisms so as to change from an initial to a finish lapping pressure after a predetermined initial or rough lapping operation and to relatively separate said lapping elements after a further predetermined 15 finish lapping operation.

3. A lapping machine of the type having a pair of opposed relatively rotatable lapping elements which are movable relatively toward and from each other and a work carrying cage therebetween arranged to carry a plurality of work pieces through an irregular path between the operative faces of said lapping elements, a mechanism arranged to cause a relative approaching and receding movement between said lapping elements, 20 means including a control lever arranged to cause either an approaching or receding movement between said lapping elements, means to apply a predetermined pressure for an initial lapping operation for a predetermined time interval, a second pressure regulating mechanism arranged to maintain the laps in engagement with the work at a second predetermined pressure for a final or finish lapping operation, and an electrical time delay relay arranged automatically to control 25 said pressure mechanisms so as to change from an initial to a finish lapping pressure after a predetermined initial or rough lapping operation and relatively to separate said lapping elements after a further predetermined finish lapping 30 operation.

4. In a lapping machine, opposed relatively rotatable lapping wheels and a work cage therebetween, means to cause a relative approaching and receding movement between said lapping wheels, 35 manually operable means to control said mechanism to cause either an approaching or receding movement between said lapping elements, a solenoid operatively connected therewith to cause a receding movement between said lapping elements, adjustable means to apply a relatively high 40 pressure between the laps and work for an initial or rough lapping operation, means to apply a relatively low pressure between the laps and the work for a final or finish lapping operation, means 45 including a solenoid to render said latter means operative, and an electrical control system including an electrical time delay relay which serves after a predetermined time interval of rough lapping to energize said second solenoid and render 50 said low pressure device operative for a final or finish lapping operation, and to energize said first solenoid after a further predetermined time interval of finish lapping operation automatically to separate said lapping wheels.

5. A lapping machine of the type having a pair of opposed relatively rotatable lapping elements which are movable relatively toward and from each other and a work carrying cage therebetween arranged to carry a plurality of work pieces 55 through an irregular path between the operative faces of said laps, a fluid pressure system includ-

6 operative faces of said laps, a fluid pressure system including a piston and cylinder which are arranged to cause a relative approaching and receding movement between said lapping elements, a fluid pressure system including a control valve arranged to convey fluid under pressure to either end of said cylinder, a pressure regulating valve to maintain said laps in engagement with the work at a predetermined pressure for an initial or rough lapping operation, a second pressure regulating valve arranged to maintain said laps in engagement with the work at a second predetermined pressure for a final or finish lapping operation, an adjustable stop to limit the approaching movement of said lapping elements, and means to automatically control said pressure regulating valves so as to shift from an initial to a final lapping pressure automatically after a predetermined initial lapping operation.

7. A lapping machine of the type having a pair of opposed relatively rotatable lapping elements which are movable relatively toward and from each other and a work carrying cage therebetween arranged to carry a plurality of work pieces through an irregular path between the operative faces of said laps, a fluid pressure system including a piston and cylinder which are arranged to cause a relative approaching and receding movement between said lapping elements, a fluid pressure system including a control valve to convey fluid under pressure to either end of said cylinder, a pressure regulating valve to maintain said laps in engagement with the work at a predetermined pressure for an initial or rough lapping operation, a second pressure regulating valve arranged to maintain the laps in engagement with the work at a second predetermined pressure for a finish lapping operation, and a time delay relay arranged automatically to control said valves so as to change from a high to a low pressure after a predetermined initial or rough lapping operation and to relatively separate said lapping elements after a further predetermined finish lapping operation.

8. A lapping machine comprising opposed relatively rotatable lapping wheels and a work cage therebetween, means including a piston and cylinder operatively connected to cause a relative approaching and receding movement between said lapping wheels, a fluid pressure system including a control valve to control fluid to said cylinder, a pressure regulating valve in said system which is adjusted for an initial or rough lapping operation, a second pressure regulating valve which is adjusted for a final or finish lapping operation, a valve associated with said second pressure regulating valve to render it inoperative during the initial lapping operation, means including a solenoid to open said latter valve, and an electrical control system including a time delay relay which serves to energize said solenoid to open said valve and render the second pressure regulating valve operative after a predetermined rough or initial lapping operation, to reverse said control valve to relatively separate said lapping wheels after a further predetermined period of finish lapping.

9. A lapping machine of the type having a pair of opposed relatively rotatable lapping elements which are movable relatively toward and from each other and a work carrying cage therebetween arranged to carry a plurality of work pieces through an irregular path between the operative faces of said laps, a fluid pressure system includ-

cause a relative approaching and receding movement between said lapping elements, means including a control valve to convey fluid under pressure to either end of said cylinder, a pressure regulating valve arranged to maintain the laps in engagement with the work at a predetermined pressure for an initial or rough lapping operation, a normally inoperative second pressure regulating valve arranged to maintain said laps in engagement with the work at a second predetermined pressure for a final or finish lapping operation, and an electrical control system including a time delay relay which is operatively connected automatically to render said second pressure regulating valve operative after the initial or rough lapping operation has continued for a predetermined time interval and automatically to separate said lapping elements after the final or finish lapping operation has continued for a further predetermined time interval.

9. A lapping machine of the type having a pair of opposed relatively rotatable lapping elements which are movable relatively toward and from each other, a work carrying cage arranged to carry a plurality of work pieces for a simultaneous lapping operation between said laps, means including a fluid pressure piston and cylinder operatively connected to move one of said laps relatively toward and from the other, a fluid pressure system including a control valve, an adjustable pressure regulating valve in said system to obtain a predetermined pressure between said laps and work pieces for an initial lapping operation, a second adjustable pressure regulating valve which is adjusted to cause said laps to lap the work at a second predetermined pressure for a final lapping operation, and an electrical control system including a time delay relay which is rendered effective when the laps move into operative engagement with the work to allow the rough or initial lapping operation to proceed for a predetermined time interval, after which the second pressure regulating valve is rendered operative, and to thereafter automatically shift said control valve to separate said lapping elements after the final or finish lapping operation has proceeded for a further predetermined time interval.

10. In a lapping machine, opposed relatively rotatable lapping wheels and a work cage therebetween, means including a piston and cylinder operatively connected to cause a relative approaching and receding movement between said lapping wheels, a fluid pressure system including a control valve to control the flow of fluid to and from said cylinder, manually operable means to shift said valve to cause either an approaching or a receding movement of said lapping wheels, an electrical solenoid which is arranged to shift said control valve to cause a receding movement between said lapping elements, a pressure regulating valve which is adjusted for an initial or rough lapping operation, a second pressure regulating valve which is adjusted for a final or finish lapping operation, said second pressure regulating valve being inoperative during the rough lapping operation, a solenoid to render said second valve operative, and an electrical control system including a time delay relay which is rendered operative when the lapping wheels approach the work pieces and which serves after a predetermined time interval of rough lapping to energize the

second solenoid to render the second pressure regulating valve operative to produce a predetermined pressure for a final or finish lapping operation, and after a further predetermined time interval of finish lapping to energize said first solenoid to shift the control valve and thereby to cause a relative separating movement of said laps.

11. A lapping machine of the type having a pair of opposed relatively rotatable lapping elements one of which is movable relatively toward and from the other, a work cage therebetween for simultaneously supporting a plurality of work pieces for a simultaneous lapping action between the opposed faces of said laps, means comprising a pair of spaced fluid pressure cylinders arranged on diametrically opposite sides of the axis of the movable lap, pistons within said cylinders which are operatively connected to cause a relative approaching and receding movement between said laps, a fluid pressure system including a control valve arranged to simultaneously admit fluid under pressure to either end of said cylinders, a pressure regulating valve in said system which is arranged to regulate the pressure of fluid so as to cause the laps to be maintained in engagement with the work at a predetermined pressure for an initial lapping operation, a second pressure regulating valve in said system to maintain the laps in lapping engagement with the work at a second predetermined pressure for a finish lapping operation, and means including an electrical time delay relay arranged to automatically render said first pressure regulating valve inoperative after a predetermined time interval.

12. A lapping machine of the type having a pair of opposed relatively rotatable lapping elements one of which is movable relatively toward and from the other, a work cage therebetween for simultaneously supporting a plurality of work pieces for a simultaneous lapping operation between the opposed faces of said laps, and means comprising a pair of spaced fluid pressure cylinders arranged on diametrically opposite sides of the axis of the movable lap, pistons within said cylinders which are operatively connected to cause a relative approaching and receding movement between said laps, a fluid pressure system including a control valve arranged to simultaneously admit fluid under pressure to either end of said cylinders, a pressure regulating valve in said system which is arranged to regulate the pressure of the fluid so as to cause the laps to be maintained in engagement with the work at a predetermined pressure for an initial lapping operation, a second pressure regulating valve in said system which is arranged to be adjusted to maintain the laps in lapping engagement with the work at a second predetermined pressure for a finish lapping operation, and an electrical control system including an electrical time delay relay which is rendered operative when the laps move into engagement with the work automatically to allow a rough or initial lapping operation to continue for a predetermined time interval, to render said second pressure regulating valve operative after a predetermined rough lapping operation, to shift the main control valve after a final or finish lapping operation for a further predetermined time interval to separate the lapping elements from engagement with the work.
